UNITED STATES PATENT OFFICE.

CARL FISHER, OF BRIDGEPORT, CONNECTICUT.

COMBINED SAFETY-PIN AND CLASP.

1,340,533.

Specification of Letters Patent. Patented May 18, 1920.

Application filed November 19, 1919. Serial No. 339,182.

To all whom it may concern:

Be it known that I, CARL FISHER, a citizen of Germany, and residing at Bridgeport, in the county of Fairfield and State of Connecticut, have invented new and useful Improvements in Combined Safety-Pins and Clasps, of which the following is a specification.

My invention relates to a combined safety-pin and clasp, made of a single length of resilient wire and embodying a point and a keeper therefor, the device being so constructed as to admit of the disengagement or release of the point with its keeper by a mere relative movement of the back of the pin, accomplished in such manner that the point is held in proper position to pierce the article or fabric to which the pin is to be attached. Another object is the provision of a device of the above character which is very simple as well as strong and durable in construction, which may be manufactured at small cost and which is highly convenient and serviceable in practical use.

A still further object is the provision of certain improvements in the combined safety-pin and clasp disclosed in my United States Letters Patent No. 1,192,613, granted July 25, 1916.

For a full understanding of the invention, reference is to be had to the following description and accompanying drawing, forming a part of this specification, and in which:—

Figure 1 is a side elevational view of a combined safety-pin and clasp made in accordance with my invention.

Fig. 2 is an enlarged section, taken on the line 2—2 of Fig. 1.

Figs. 3 and 4 illustrate the use of my device as a watch guard and neck-tie clasp, respectively.

As clearly illustrated in the accompanying drawing, the device is made of a single strand of resilient wire, substantially of the same cross-section throughout, except as hereinafter stated, and is formed with a straight back portion 5, bent or doubled upon itself at 6 to provide a hook portion 7,

which inclines outwardly with respect to the back portion, and which is tapered to a sharp piercing point 8.

At its opposite end, the back is bent or doubled upon itself at 9, the curve being larger than that at 6, and thence it proceeds toward the point in a parabolic line 10, the

returning or incoming line on its outer side being recessed longitudinally at 11 to receive the point 8 and to form a keeper therefor. Continuing from this recess, the wire is gathered into a strong spiral heap 12, slidably pressing on the side of the back 5 and partly projecting into a plane above the back as shown. The provision of the outwardly inclined hook 7, taken in connection with the parabolic line and the spiral heap, affords a firm foundation for an effective clasping or shutting engagement between the piercing point and its recessed region or keeper. Moreover, the strong spiral heap, which, as will be understood from an inspection of Fig. 1, has an outward bend in order slidably to engage the side of the back, is relatively yieldable outwardly so as to permit an article to be passed between itself and the back. Owing to the resiliency of the material of which the device is made, the back may be readily pressed toward the parabolic line, disengaging the point from its keeper in an obvious manner and bringing the point into position either to pierce a bit of fabric or to have an article slipped upon the hook, for instance, the loop 13 of the watch 14. As soon as pressure is removed from the back, the point is automatically reseated in its recess. The loop engaged on the hook is then slipped between the spiral heap and the back and thence upon the parabolic portion.

Fig. 4 shows my device attached to neck-tie 15. When the hook has been opened, as above described, the point is pierced through the fabric, and then the pin is advanced, with the hook underneath and the spiral heap on top, until as much of the fabric as desired is engaged, whereupon the point is repierced through the fabric and engaged with its keeper. The bit of engaged fabric may be permitted to rest on the back, or the pin may be swung around until the same rests on the parabolic portion as shown in Fig. 4. The illustrations show only two of the preferred uses of my device, and many other equally advantageous uses will readily suggest themselves.

Having thus described my invention, what I claim is:—

1. A combined safety-pin and clasp made of a single strand of resilient wire having a straight back portion, a hook outwardly inclined with respect thereto and terminating in a piercing point, a parabolic portion in

plan with said hook and recessed to form a keeper for said hook, said parabolic portion terminating in a firm spiral heap.

2. A combined safety-pin and clasp made
5 of a single strand of resilient wire having a straight back portion and bent upon itself at one end to form a hook which inclines outwardly with respect to the back portion and which is tapered to a piercing point, the opposite end being also bent upon itself in a 10 larger curve than the hooked end and then

proceeding in a parabolic part in plan with the hook, said parabolic part being longitudinally recessed adjacent the piercing point to receive the same and to form a 15 keeper for the hook and the same terminating in a firm spiral heap which slidably engages the straight back and projects into a plane therebeyond.

In testimony whereof I have signed my 20 name to this specification.

CARL FISHER.
